METHOD OF MAKING HANDBAG FRAMES

Frank J. Quigan, Bayside, N. Y.

Application April 6, 1937, Serial No. 135,223

3 Claims. (Cl. 113—116)

This invention relates to a method of making handbag frames, and has for its primary object and purpose to provide a method whereby the fabrication of frame members of the type in which one of the side walls is provided at its outer edge and throughout the length of said member with a continuous transversely disposed flange, may be expeditiously fabricated from strip steel stock, so that an appreciable reduction in manufacturing costs of frames of this type is realized.

More particularly, my new method consists, essentially, in first cutting openings in the length of steel strip at longitudinally spaced points, each opening having opposed edges converging to a meeting point in spaced relation to one longitudinal edge of the strip and additional opposed converging edges intersecting the other longitudinal edge of the strip at spaced points, then transversely bending the metal strip along spaced longitudinal lines to provide a channel therein, then transversely bending one longitudinal edge portion of the strip along a line tangent to the meeting ends of said first named converging edges of the openings to provide a continuous transversely disposed flange, and then bending said flange at said meeting ends of the converging edges to provide an intermediate frame section and end sections extending at right angles thereto and dispose the opposed converging edges of the frame walls in abutting contact with each other.

The method further comprises the formation of tongues in the frame strip projecting into each of the openings cut therein and adapted to be subsequently bent over upon the base wall of the channel of one of the frame sections and welded thereto, whereby the abutting ends of the walls of the frame sections are maintained in close contact with each other.

With the above and other objects in view, the invention consists in the improved method of making handbag frames, as will be hereinafter more fully described, illustrated in the accompanying drawing and subsequently incorporated in the subjoined claims.

In the drawing wherein I have illustrated the several steps of my new method in a preferred embodiment thereof, and in which similar reference characters designate corresponding parts throughout the several views:

Fig. 1 is a plan view of a length of metal strip stock showing the openings and tongues formed therein, in the first step of the method,

Fig. 2 is a side elevation showing the frame

strip after it has been bent into channel shaped form,

Fig. 3 is a similar view illustrating the following step whereby the longitudinally continuous transverse flange is formed on one of the frame walls,

Fig. 4 is a side elevation of the completed frame member,

Fig. 5 is a perspective view of two of the frame members hingedly connected at their corresponding ends and constituting a complete bag frame,

Fig. 6 is a transverse sectional view taken on the line 6—6 of Fig. 2,

Fig. 7 is a similar sectional view taken on the line 7—7 of Fig. 4, and

Fig. 8 is a vertical fragmentary sectional view illustrating the method of permanently securing the adjoining ends of adjacent frame sections to each other.

Referring in detail to the drawing, I have shown in Fig. 1 thereof, the flat strip steel blank 5, which is fed through the die stamping or cutting machine from a reel and cuts the stock into sections of predetermined length and provides each of said sections in properly spaced relation to the ends thereof, with an opening of general rectangular form. Each of these openings has the opposed edges 6 converging towards one longitudinal edge of the metal strip, the meeting ends 7 of said converging edges being suitably spaced from said longitudinal edge of the strip.

Each of said die cut openings in the metal strip also has the opposed edges 8 converging towards each other and intersecting the other longitudinal edge of the strip 5 at their adjacent ends, which are suitably spaced apart, as indicated at 9.

At one side of each opening, in the metal strip and at the inner adjacent ends of one of the edges 6 and 8, the metal strip is formed with a tongue 10 projecting longitudinally into the opening. At the inner ends of the other edges 6 and 8 and opposite to the tongue 10, the metal strip is formed with the rectangular notch or recess 11.

Simultaneously with the cutting of said spaced openings the frame length of metal stock is severed from the strip and formed at each end thereof, with a longitudinally projecting tongue 12.

After the die stamping of the frame blank, illustrated in Fig. 1, the movement thereof through the machine is continued, and in the next operation the strip 5 is transversely bent throughout its length along the spaced parallel lines, indicated at A, which coincide with the

opposite ends or corners of the notches 11. Thus the frame strip is formed into a channel 13, as seen in Fig. 6 of the drawing, said channel having one side wall 14 disposed at right angles to the base wall 15 of the channel, and the opposite side wall 16, which is relatively narrow, at a short distance above the base wall 15 is bent to extend outwardly in divergent relation from the wall 14.

In the following operation, the longitudinal edge portion of the wider channel wall 14 is transversely bent along the longitudinal line B which is tangent to the meeting ends 7 of the opposed edges 6 at the ends of the intermediate and end sections of the channel wall 14. There is thus formed a continuous transverse projecting flange 17 at the outer edge of the wall 14, the free edge of which is suitably spaced from the edge of the channel wall 16, as more clearly shown in Fig. 7 of the drawing.

20 The channeled frame strip, as thus formed, consists of a longitudinal intermediate section and relatively short end sections integrally connected with each other only by the transverse flange 17. The opposing end edges 8 of the walls 16 of said frame sections are positioned in substantially parallel relation to the opposed edges 6 of the walls 14 of said frame sections while the tongues 10 project longitudinally from the base walls 15 of the frame sections.

30 After the flange 17 is formed, as above described, the channeled frame strip is then positioned upon suitable supporting pins or rods engaged with said strip at the meeting ends of the opposing edges 6 and in contact with the under side of the flange 17. The relatively short end sections D of the frame strip are now bent downwardly with respect to the long intermediate section C to extend at right angles to the latter. The opposing edges 6-6 and 8-8 of the channel walls of said frame sections are thereby brought into substantially abutting contact with each other to form the miter joints as indicated at 6' and 9' respectively. The flange 17 as it is bent around the supporting pins or rods produces the rounded corners 18 at the outer ends of the miter joints 6' and assures the unbroken integral continuity of the flange 17 throughout the length of the frame sections C and D.

35 The tongues 10 projecting from one of the frame sections are now bent over upon base wall 15 of the channel of the abutting frame section, said tongue at the bend thereof being received in the rectangular notch 11. These tongues are then securely welded to the base walls of the abutting frame sections whereby close abutting contact of the channel walls of said frame sections is maintained and separation at the miter joints 6' and 9' is effectually prevented.

40 The tongues or extensions 12 at the free ends 60 of the sections D of the frame member are now bent to form the cylindrical hinge knuckles 19. These knuckles receive suitable pintles 20 whereby two complementary frame members are hingedly connected with each other at their corresponding ends in the conventional manner, as seen in Fig. 5 of the drawing.

45 From the above description it will be seen that I have devised a method of expeditiously making such bag frame members from strip steel stock which may be readily carried out by automatic machinery. This method produces a channeled bag frame member having a continuous transverse top flange projecting outwardly from the inner channel wall with accurately abutting contact of the channel walls at the miter joints be-

tween the horizontal intermediate section and the vertical end sections or legs of the frame member. The locking engagement of the tongues 10 in the notches 11 also relieves the welds of excessive strains and effectively prevents any relative transverse shifting of the frame sections at the miter joints 6' and 9'. Thus a substantial frame structure is produced from relatively light steel strip stock and at comparatively low manufacturing cost. The bag or pouch fabric is connected with the frame members in the usual manner, by inserting the edges thereof within the frame channel 13 beneath the flange 17 and then applying a compressing pressure against the channel walls 16 to securely clamp and hold the bag fabric within the frame channel. This fabric of course, extends over and completely conceals the outer walls 16 of the frame channel.

50 In the foregoing description, I have referred to a practical embodiment of my present invention which has given highly satisfactory results in practice. Nevertheless, it will be understood that this same method might be advantageously employed in the production of bag frames of other outline contour or form than that shown in the drawing, and that minor mechanical variations might also be adopted in the details of construction of the frame. Therefore, it is to be understood that in these and other particulars, I reserve the privilege of adopting such modifications or changes as may fairly be considered to be within the scope and spirit of the appended claims.

I claim:

1. In a method of making a bag frame member, 35 first cutting a blank from metal strip stock and forming longitudinally spaced substantially rectangular openings therein to provide intermediate and end sections, with the opposed ends of said sections having opposing edges at each side 40 of the longitudinal center line of the blank converging towards each other, the opposed edges at one side of said center line meeting at a point in spaced relation to one longitudinal edge of the blank and the other opposed converging edges 45 intersecting the opposite longitudinal edge of the blank at spaced points, then bending said blank throughout its length along spaced parallel longitudinal line between said oppositely extending opposed converging edges of the blank sections 50 to form the same into channel shape having opposite side walls of relatively different widths, then bending the longitudinal edge portion of the wider channel wall along a longitudinal line tangent to the meeting ends of said first named 55 opposed converging edge of the strip sections to form a continuous flange, and then bending said flange between said sections to dispose the end sections of said strip at an angle to the intermediate section and position the opposed converging edges of the side walls of said frame sections in substantially abutting contact with each other.

2. In a method of making a bag frame member, 60 first cutting a blank from metal strip stock and forming longitudinally spaced substantially rectangular openings therein to provide intermediate and end sections, with the opposed ends of said sections having opposed edges at each side of the longitudinal center line of the blank converging 65 towards each other, the opposed edges at one side of said center line meeting at a point in spaced relation to one longitudinal edge of the blank and the other opposed converging edges intersecting the opposite longitudinal edge of the 70

blank at spaced points, then bending said blank throughout its length along spaced parallel longitudinal lines between said oppositely extending opposed converging edges of the blank sections 5 to form the same into channel shape having opposite side walls of relatively different widths, then bending the longitudinal edge portion of the wider channel wall along a longitudinal line tangent to the meeting ends of said first named 10 opposed converging edges of the strip section to form a continuous flange, then positioning the frame strip upon spaced supporting rods in contact with the underside of said flange at the meeting ends of said opposed converging edges, 15 and then bending the flange around said supports to dispose the end sections at an angle to the intermediate section and position the opposed converging edges of the walls of said frame sections in substantially abutting contact with each 20 other.

3. In a method of making a bag frame member, first cutting a blank from metal strip stock and forming longitudinally spaced substantially rectangular openings therein to provide intermediate 25 and end sections, with the opposed ends of said sections having opposing edges at each side of the longitudinal center line of the blank converging towards each other, the opposed edges at

one side of said center line meeting at a point in spaced relation to one longitudinal edge of the blank and the other opposed converging edges intersecting the opposite longitudinal edge of the blank at spaced points, and simultaneously forming the opposed ends of said sections with complementary interlocking parts, then bending said blank throughout its length along spaced parallel longitudinal lines between said oppositely extending 5 opposed converging edges of the blank sections to form the same into channel shape having opposite side walls of relatively different widths, then bending the longitudinal edge portion of the wider channel wall along a longitudinal line tangent to the meeting ends of said first named 10 opposed converging edges of the strip sections to form a continuous flange, and then bending said flange between said sections to dispose the end sections of said strip at an angle to the intermediate section and position the opposed converging edges of the side walls of said frame sections in substantially abutting contact with each other, and then permanently securing said complementary parts at the abutting ends of the frame sections in interlocking engagement with 15 each other to prevent relative displacement of 20 said abutting ends of the frame sections. 25
